UNITED STATES PATENT OFFICE.

SIMEON W. ALBEE, OF CHARLESTOWN, NEW HAMPSHIRE, ASSIGNOR TO HIMSELF, AND HENRY HODSON, OF CHARLESTOWN, MASSACHUSETTS.

IMPROVEMENT IN APPARATUS FOR INHALING GAS.

Specification forming part of Letters Patent No. 42,721, dated May 10, 1864.

To all whom it may concern:

Be it known that I, SIMEON W. ALBEE, a resident of Charlestown, in the county of Sullivan and State of New Hampshire, have invented an Improved Apparatus for the Inhalation of Nitrous Oxide or other Gas or Vapor; and I do hereby declare the same to be fully described in the following specification and represented in the accompanying drawings, of which—

Figure 1 denotes a side elevation, and Fig. 2 a vertical and longitudinal section of it. Fig. 3. is an end view of the mouth-tube.

The nature of my invention consists in the combination of an elastic inflexible mouth-cushion with a mouth tube or conduit and its valve or valves, as described; also, in a peculiar combination and arrangement of valves, valve seats, and valve stem, with the mouth-tube and valve-case arranged as specified.

In the drawings, A denotes the valve-case, which is cylindrical and tubular, and formed so that its lower end may be fitted in and fastened to the mouth of a gas bag or a conduit leading therefrom or from a gas-reservoir. Within the said valve-case are two valve-seats, a b, through openings of which a valve-stem, c, extends and is furnished with two valves, d e, the upper of which (viz., that marked d) being above the seat a, while the lower (or that marked e) is below the seat b. The two valves are also so arranged that when either may be closed against its seat the other will be off its seat. Furthermore, there is a spring, f, arranged on that part of the stem c which projects below the valve e, the said spring being made to rest on a stationary cross-bar, g, and to operate so as to force the valve-stem upward and close the lower valve against its seat. The valve-stem is to be surmounted by a button or head, h.

A tubular conic frustum or mouth-tube, B, is joined at its smaller end to the valve-case, and projects at right angles thereto and opens into it between the two valve seats a and b, the whole being as shown in Figs. 1 and 2. The larger end of this mouth-tube is provided with a elastic inflatable mouth-piece or cushion, C, made of vulcanized caoutchouc or other suitable air-tight material. This cushion is annular in shape and formed to go around the mouth or about the mouth and across the nose of a person, and to fit closely to the external surfaces thereof when pressed

against the same, the object of the cushion being to make a close joint about the mouth or breathing-orifices of the nose and mouth, in order that a person using the apparatus may be able to inhale and exhale a gas through it.

The elastic cushion should be provided with a nozzle, i, having a suitable screw-cap (or its equivalent) for closing such nozzle and for enabling air to be blown through the nozzle and into the cushion, or be expelled from the cushion, as circumstances may require.

In using the apparatus when coupled to a gas-bag or gasometer containing nitrous-oxide gas, the operator is to apply the cushion C to the face and mouth of the person or patient to whom the gas is to be administered, the operator at the same time holding the apparatus in one hand by the part A, and having the index-finger of such hand placed on the top of the button or head h of the valve-stem. Under these circumstances the valve d will be open and the valve e will be closed, so that no gas can escape from the bag, the patient in the meanwhile breathing or inhaling and exhaling common atmospheric air, which he will do through the opening of the valve-seat a. After a short time, and when the patient may have become accustomed to the apparatus, so as to breathe naturally through it, the operator is to quietly press downward the valve-stem so as to close the valve d down upon its seat a and open the valve e, or press it away from its seat b, which having been done the gas will pass into the valve-case and from thence be drawn through the mouth-tube B and into the lungs of the patient.

If desirable, a mixture of air and gas may be breathed by the patient, such being accomplished by slightly depressing the valve-stem, so as to cause both of its valves to be open.

I claim as my invention—

1. The combination of the elastic inflatable mouth-cushion C with the mouth-tube or conduit B, and its valve-case A, provided with valves or a valve apparatus, as described.
2. The combination and arrangement of the two valves, valve-seats, and valve stem together, and with the valve-case and a mouth-tube arranged as described.

SIMEON W. ALBEE.
